UNITED STATES PATENT OFFICE

CARL HORIX, OF CHICAGO, ILLINOIS

MOUNTING FOR EMBLEMS OR THE LIKE

Application filed April 2, 1928. Serial No. 266,480.

My present invention relates to an improved emblem or the like mounting and has for its primary object to provide a convenient, practical and simple means for mounting emblem carrying pieces, name, number or initial plates upon a mounting surface or base member.

A further object of the invention is to provide a mounting for the devices above enumerated which will not take away from the attractiveness of the mounting or base member to which the devices are applied but, on the other hand, which will enhance the appearance of the mounting or base member and make the combined assembly one of unique attractiveness while also of special usefulness for denoting, as an example, ownership.

Other objects of the invention will appear hereinafter, the novel features and combinations being set forth in the appended claims.

In the accompanying drawing:

Fig. 1 is a view in plan of a belt buckle illustrating the application of one form of my invention;

Fig. 2 is a similar view of a belt buckle illustrating a slightly modified form of my invention;

Fig. 3 is a view in cross section on the line 3—3 of Fig. 1;

Fig. 4 is a view in cross section on the line 4—4 of Fig. 2;

Fig. 5 is a detail perspective view of the emblem piece illustrated as applied to the buckle in Fig. 1;

Fig. 6 is a detail perspective view of the emblem piece applied to the buckle in Fig. 2;

Fig. 7 is a plan view of another form of the mounting;

Fig. 8 is a similar view of still another form of the mounting;

Fig. 9 is a view in cross section on the line 9—9 of Fig. 7; and

Fig. 10 is a view in cross section on the line 10—10 of Fig. 8.

For the purpose of illustrating the salient features of the invention, I have shown the same as applied to belt buckles. However, it is to be understood that it is in no way limited to this particular adaptation as the invention may also be used as a very practical

and desirable means for applying emblems, initials or the like to automobiles, articles of stationery, cigarette cases, vanity cases, or any other instances where it is desirable to apply a crest, numbers, initials, or the like to a mounting.

Using the present illustration as an example, 5 represents the belt buckle which I will hereinafter refer to as a base member. The buckle in this respect being provided with the usual parts for holding the belt 6.

According to one form of the invention, and as particularly illustrated in Fig. 3, I provide a plurality of countersunk areas 7 in the face of the buckle 5, the same being produced preferably by a suitable punching operation. At the same time, I also provide an opening 8 within each of the countersunk areas 7 with the opening preferably extending through the thickness of the base member or buckle. These countersunk areas 7 are made for the reception of each of a plurality of separately formed emblem pieces 9 which are shaped to correspond to the shape of the countersunk areas 7 so that they snugly fit therein. In the case of an oval shaped emblem piece, as illustrated in Fig. 1, which, due to its shape, cannot turn or rotate in the countersunk areas, I employ a round rivet 10 (see Fig. 5), the same being integrally or otherwise formed on the underside of the emblem piece and adapted to extend through the opening 8 made to receive it in the base member 5. An instrument or tool suitable for the purpose is then caused to engage the rivet 10 from the back of the base member to flange or clinch the same in the opening 8. The separately formed emblem pieces are preferably made of metal, although they may be made of other material; in any event, their thickness should be the same as that of the depth of the countersunk areas in which they are mounted so as to leave their faces flush with the face of the base member. The rivets 10 in this respect should also be of the same depth as the openings 8 in which they are received, so as to leave the back of the base member perfectly smooth. This is preferable but not essential in all forms of the invention.

In some cases it will be desirable to employ

circular emblem pieces such as illustrated at 9' in Fig. 2. In this case, the countersunk areas 7', see Fig. 4, are also circular. Since the circular emblem pieces have a tendency to rotate in the countersunk areas 7', it becomes desirable to provide for special riveting means to guard against this rotation. I accomplish this special purpose by means of the square rivet 10' illustrated in Fig. 6. The 10 openings 8' in the base member which receive these square rivets, are made correspondingly square so that after the rivet is flanged or clinched, as shown in Fig. 4, the square opening for the rivet will prevent rotation of the 15 circular emblem pieces.

In Fig. 7 I have illustrated a modified form in which the base member 5 is made with a plurality of punched openings 11, a pair of openings for each of the emblem pieces, the 20 openings being positioned in the base member at diametrically opposite sides of the area to be occupied by the emblem pieces. In this form of the invention, the emblem pieces 12, see Fig. 9, are made with pins, spurs, or the 25 like 13 which extend into the openings 11 and with their ends clenched over the back of the base member 5, as at 14. These emblem pieces may be punched out of metal or formed of any other material suitable for the purpose 30 and the pins, spurs or the like 13 are preferably formed integral therewith and bent at right angles to extend through the openings. The areas on the face of the base member 5 to be occupied by these emblem 35 pieces 12 may be countersunk so as to inset the emblem pieces, if desired, or the emblem pieces may be simply superimposed upon the surface of the base member, as shown to best advantage in Fig. 9.

40 According to the form of the invention illustrated in Fig. 8, the face of the base member 5 is provided with countersunk areas 15 for insetting the emblem pieces. The emblem pieces for this form are preferably 45 square, hexagon-shape, or for that matter, any other desirable shape, instead of circular, as shown in Fig. 7. Instead of employing only two pins, spurs, or the like for this form, each of the emblem pieces will be made with 50 four pins or spurs 13.

As shown in Figs. 8 and 10, the emblem piece is shown as at 16, the same being inset in the countersunk area 15 and the pins or spurs extend through the four openings 11 55 for each piece with their ends clinched as at 18, in the same manner as the ends 14 of the pins or spurs 13, shown in Fig. 9.

In all the forms illustrated, it will be readily seen that the emblem pieces are impaled 60 on the base member 5 and held against rotation or other relative movement so that there is no chance of them working loose, becoming lost, or getting out of alignment, that any one of the forms may be conveniently 65 applied to the base member without in any

way interfering with any device or mechanism that it may be desirable to apply to the back of the base member, that the pieces will attractively display whatever marking with which they are equipped.

70 It is of course understood that the base member 5 will usually be made of metal and that, aside from the areas occupied by the emblem pieces, the face of the same may be decorated as desired and in this connection 75 colors may be used which will blend or contrast with the colors of the emblem pieces, if they happen to be made in colors, or the emblem pieces may otherwise be decorated to blend with the decorations of the base 80 member.

Considering the invention as applicable to belt buckles, any one desiring to purchase a belt buckle and use the same with his initials may pick out the proper initials from a quantity of the emblem pieces, and the emblem pieces thus selected may then be quickly and conveniently applied to the belt buckle. The emblem pieces need not all be used for initial purposes as it may be desirable to use 90 one initial, as an example, and two crests or designs, or for that matter, any combination may be used that is desired.

95 Obviously those skilled in the art may make various changes in the construction and arrangement of parts without departing from the spirit and scope of the invention as defined by the claims hereto appended and I wish therefore not to be restricted to the precise construction herein disclosed.

100 I claim:—

1. An emblem or the like mounting comprising an emblem carrying piece having a hollow circular rivet projecting from one side thereof for impaling said piece upon a 105 base member.

2. A mounting for emblems or the like comprising a base member, a countersunk area in one face thereof, a tapered opening extending from said countersunk area to the 110 opposite face of said base member, and an emblem carrying member comprising a portion adapted to fit within said countersunk area and a portion for extending into said opening adapted to be clinched therein 115 against the tapered sides of said opening.

3. A mounting for emblems or the like comprising a base member, a non-circular countersunk area in one face thereof, an opening extending from said countersunk area to the 120 opposite face of the base member, and an emblem carrying member comprising a portion adapted to fit snugly within said countersunk area and a portion for extending into said opening adapted to be clinched 125 therein.

4. A mounting for emblems or the like comprising a base member, a countersunk area in one face thereof, a square opening extending from said countersunk area to the opposite

face of said base member, and an emblem carrying member comprising a portion adapted to fit within and substantially fill said countersunk area and a square portion for extending into said opening adapted to be clinched therein.

5. A mounting for emblems or the like comprising a base member, a countersunk area in one face thereof, an opening extending from 10 said countersunk area to the opposite face of said base member, and an emblem carrying member comprising a portion adapted to fit within and substantially fill said countersunk area and having a split rivet thereon 15 for extending into said opening and adapted to be swaged to hold said emblem carrying member within said countersunk area.

6. A mounting for emblems or the like comprising a base member, a countersunk area in 20 one face thereof, an opening extending from said countersunk area to the opposite face of said base member, and an emblem carrying member comprising a portion adapted to fit within said countersunk area and a circular 25 portion thereon having an opening therein adapted to be swaged to hold said emblem carrying member in place.

7. A mounting for emblems or the like comprising a base member having a countersunk 30 area in one face thereof, a member adapted to fit within and completely fill said countersunk area, a plurality of projections on said member, a plurality of openings extending from said countersunk area to the opposite 35 face of the base member, said projections on said member being adapted to extend through said openings and be clinched against the opposite side of said base member.

8. A mounting for emblems or the like comprising a base member, a separately formed 40 emblem piece, a countersunk area in the face of said base member for the reception of said emblem piece having an opening therein, said emblem piece being adapted to substantially 45 fill said countersunk area, and means for holding said emblem piece in said countersunk area so that the face thereof is flush with the face of the base member comprising a rivet on the back of the emblem piece 50 adapted to be clinched in said opening.

9. A mounting for emblems or the like comprising a base member, a plurality of separately formed circular emblem pieces, and means for attaching said emblem pieces to 55 said base member comprising a square rivet on said emblem pieces co-operating with a tapered opening substantially square in cross section, said rivet being swaged so that it engages the sides of said opening without 60 being clinched over the edges of said opening which are adjacent said opening on the under face of said base member.

10. A mounting for emblems or the like comprising a base member, a countersunk 65 area in one face thereof, a tapered opening

extending from said countersunk area to the opposite face of said base member, and an emblem carrying member comprising a portion adapted to fit within said countersunk area and a circular portion thereon having 70 an opening therein, said circular portion being adapted to be swaged against the sides of said tapered opening to hold said emblem carrying member in position.

11. A mounting for emblems or the like comprising a base member, a countersunk area in one face thereof, a tapered opening extending from said countersunk area to the opposite face of said base member, and an emblem carrying member comprising a portion adapted to fit within said countersunk area and a circular portion thereon having 80 an opening therein, said circular portion being adapted to be swaged against the sides of said tapered opening to hold said emblem carrying member in position, said swaged portion being arranged entirely within said opening.

In testimony whereof I have signed my name to this specification on this 31st day of 90 March, A. D. 1928.

CARL HORIX.
